(57) **CLAIM**

The ornamental design for a transceiver with USB memory, as shown and described.

DESCRIPTION

FIG. 1 is a front perspective view of the transceiver with USB memory with its plug retracted, showing the new design;

FIG. 2 is a front view of the transceiver with USB memory with its plug retracted;

FIG. 3 is a rear view of the transceiver with USB memory with its plug retracted;

FIG. 4 is a side view of the transceiver with USB memory with its plug retracted;

FIG. 5 is an opposite side view of the transceiver with USB memory with its plug retracted;

FIG. 6 is a top view of the transceiver with USB memory with its plug retracted;

FIG. 7 is a bottom view of the transceiver with USB memory with its plug retracted;

FIG. 8 is a front perspective view of the transceiver with USB memory with its plug extended;

FIG. 9 is a front view of the transceiver with USB memory with its plug extended;

FIG. 10 is a rear view of the transceiver with USB memory with its plug extended;

FIG. 11 is a side view of the transceiver with USB memory with its plug extended;

FIG. 12 is an opposite side view of the transceiver with USB memory with its plug extended;

FIG. 13 is a top view of the transceiver with USB memory with its plug extended; and,

FIG. 14 is a bottom view of the transceiver with USB memory with its plug extended.
